UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,992, dated October 26, 1880.
Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

On a background, *a*, which is covered with dotted stripes, are placed series of intertwining and traversing stems, *b*, which carry notched leaves *d* and peculiar flowersee. Some of the flowers are shown in full face view, some in partial, others in full side view. All the flowers are covered with streaks running in the same oblique direction throughout the de-

sign. The leaves *d* are also streaked; but on some of the leaves the streaks run up and down, on others horizontally, as shown. The streaking of the leaves and flowers, their peculiar, apparently irregular, form, and the dotted background tend to impart to the design a peculiar bewildering appearance, in which the symmetry will, however, become apparent upon closer observation.

I claim—

1. The design for a wall-paper, consisting of the stems *b*, leaves *d*, and flowers *e*, the leaves and flowers being streaked, substantially as shown.

2. The design for a wall-paper, consisting of the stems *b*, leaves *d*, flowers *e*, and dotted background, substantially as shown.

EDUARD LEISSNER.
